ATTORNEY.

UNITED STATES PATENT OFFICE

NICOLA C. PETRILLO, OF ST. LOUIS, MISSOURI

GLOBE OR SHADE HOLDER

Application filed April 2, 1930. Serial No. 440,924.

The object of my invention is to make a globe or shade holder to be used principally for large globes or shades, such as are used for street lights in cities. A further object 5 is to make a globe or shade holder, which will prevent the breakage that now occurs in these globes or shades, which are made of glass or other fragile material. These globes are in most instances large and expensive. The 10 breakage loss is very great in actual use. The globe or shade must be removed at regular intervals in order to clean the shade or globe and in order to replace burnt out electric light bulbs. The globes or shades are 15 supported in supports, which in turn are secured to the top of posts. The actual securing means between the post and the globe or shade are screws, which pass through the support or base and come into frictional engagement with the globe or shade. The globe or shade must be held rigid in the base. This 20 requires that the screws be drawn tightly against the globe or shade. In practice the screws although made of brass or other non-rusting material corrode, so that they may 25 not be turned with the fingers. In this condition it requires a pair of pliers to turn the screws. When the pliers are used for this purpose, it is not possible to determine when 30 the screws are sufficiently tight. One or two turns of any of the screws after the screw is in positive contact with the shade or globe will crack the lower flange of the globe or shade, after which the globe or shade must be 35 replaced because it is unsafe to use such a globe or shade having such a fracture. At 40 the fracture, the globe subsequently breaks and the globe falls from its base. The specific purpose of my invention is to prevent the cracking of the lower flange of the globe or shade by introducing an annular disc against which the tightening screws come in 45 contact. By this means in the ordinary tightening of the screws, the flange of the globe or shade will not be broken. This prevents the cracking of the globe due to unequaled strains to which the lower flange of the globe is subjected when the screws come in contact with the globe or shade. Furthermore, I have 50 provided means for adjusting the length of

the split ring to take care of the slight variation in the diameter of the lower flange of the globe or shade.

A more specific object of my invention is to make this split ring as cheaply as possible. 55 To make the locking means at the free ends as elemental as possible; to provide means for adjusting the length of the split ring by simply sliding a screw secured to one free end in the slot of a finger secured to the other free 60 end.

My device may be made of few and simple parts that lend themselves readily to multiple production. With these and other objects in view my invention has relation to certain novel features of construction and arrangement of parts as will be hereinafter 65 more fully described, pointed out in the claims and illustrated in the drawing in which

Fig. 1 is a fragmental front elevation of 70 a globe or shade with my support therefor.

Fig. 2 is a sectional plan view on the line 2—2 of Fig. 1.

Fig. 3 is a fragmental sectional elevation 75 on the line 3—3 of Fig. 2.

Fig. 4 is a plan view of the split ring used in my device partly in section in its open position.

Fig. 5 is an enlarged fragmental plan view 80 of the means of connecting the ends of the split ring shown in Fig. 4.

Fig. 6 is a fragmental sectional elevation 85 on the line 6—6 of Fig. 5.

Numeral 7 indicates the globe or shade 90 holder.

Numeral 8 indicates the base or support 95 for the globe 7. The base or support 8 is annular in shape having the upper internal flange 9 and the outer wall 10 forming the annular recess 11.

Numeral 12 designates an annular depending flange positioned below the annular recess 11. The base or support 8 is secured to a pole, not shown, by means of the annular depending flange 12. On the lower portion of the globe or shade 7 is formed the conventional annular flange 13, which rests in the annular recess 11. Radial tapped holes 14 are formed on the outer wall 10. In these holes are placed in threaded engage- 100

ment the screws 15. In Fig. 2, four such screws are shown. Numeral 16 designates a split ring of substantially the same diameter as the annular flange 13. The split ring 16 is formed in two parts secured together by means of the connecting plates 17, one end of each plate being secured to one free end of the split ring 16 by means of the screws 18 and the other end of the connecting plates 17 being secured to the adjacent free end of the split ring 16 by means of one of the screws 18. In order to make the split ring 16 adjustable in length, one of the connecting plates 17 has the slot 19 cut therein. One of the screws 18 is in sliding engagement in the slot 19. It will be seen that in securing the split ring 16 initially to the globe 7, that the split ring must be opened at two places. When it is positioned on the globe, however, all the adjusting of the circumference of the split ring 16 is accomplished by sliding one of the screws 18 in the slot 19. When the proper position is secured the screw 18 in the slot 19 is screwed tightly.

When the split ring 16 is placed in the annular flange 13 of the globe 7 as shown in Fig. 3, the screws 15 are tightened into the external circumferential slot 20 formed in the split ring 16. By this means there is no contact between the screws 15 and the annular flange 13.

What I claim is:

1. A split ring having two of its free ends positively secured together by a connecting plate and its other free ends secured together by a connecting plate, which is secured at one of its ends to one of the free ends of said split ring and that is in sliding engagement on the other free end of said split ring and means for selectively securing said connecting plate on said other free end of said split ring.

2. A split ring, connecting plates, screws, two of the free ends of said split ring being secured together by means of fastening one of said connecting plates to the adjacent ends of said split ring by means of said screws, one of said connecting plates having a slot formed therein and being positively secured to one end of said split ring by means of one of said screws, the other end of said connecting plate being in sliding engagement on the adjacent end of said split ring by means of having one of said screws secured to the end of said split ring through the slot formed in one of said connecting plates.

In testimony whereof I affix my signature,
NICOLA C. PETRILLO.
